CONCRETE FORM CONSTRUCTION
APPARATUS

Paul A. Jones, Cincinnati, Ohio

Application March 4, 1930. Serial No. 433,034

13 Claims. (Cl. 140—117)

My invention is an improvement upon that of my prior Patent No. 1,794,904 dated March 3, 1931. My invention is of importance in the adjustment and assembly of forms used in present day concrete construction particularly of the type in which concrete structures are made by pouring concrete between interspaced pieces of form work. In the usual practice, the forms which are either made on the job from suitable studding and suitable sheathing or are in the form of standard sections adapted to be assembled on the job, are put up in opposed relationship so as to leave a space between for the pouring of the concrete, the opposed sections forming a mold. These sections are commonly held apart by blocks which gauge the spacing to the desired thickness of the wall or other structure, and are held together, i. e. from spreading, usually by wire ties although other ties have been used. As the concrete is poured, the spreader blocks are knocked out and removed; and after the concrete has set and the forms have been removed, the wire ties or other tie members are left in the concrete but the projecting ends thereof are cut off.

The usual practice presents a number of serious disadvantages. Where the forms are constructed on the job by nailing, the lumber is rendered unfit for most other uses and represents a considerable item of cost. Where form sections are used, the general practice has been to nail them together. This splits the wood and injures the sections thereby very greatly decreasing their life. The workmen very frequently forget to remove the spreader blocks during the pouring; and where these are left in the walls, leaks develop within a very short time. The wire ties or flat steel bands hitherto used have for the most part been secured by twisting or by nails or by wedges. These expedients also tend to injure the form work, and wires frequently stretch causing the wall or other structure to become irregular and thicker than originally intended.

The general objects of my invention are to provide a novel assembled form structure for concrete work, to provide means for fastening standard form sections together where these are used, which will not injure the forms, to provide a combination tie and spreader which eliminates the use of spreader blocks, to provide means for clamping the ends of my ties and spreaders whereby my forms or form sections may be held together against great strain, and in general to provide a form work in which the life of the component parts is indefinitely prolonged and

which may be assembled and disassembled easily and cheaply. In this connection, I make use of a clamping tool which when closed and locked not only holds adjacent form sections together but also holds and clamps my combination tie and spreader. This tool is the invention set forth and claimed in my Patent No. 1,794,904 hereinabove referred to.

These and other objects of my invention which will be set forth hereinafter or will be apparent to one skilled in the art upon reading these specifications, I accomplish by that certain construction and arrangement of parts of which I shall now describe a preferred embodiment, reference being had to the drawings which accompany these specifications.

In the drawings:

Figure 1 is a horizontal section of a portion of concrete form work showing adjacent sections held together by my clamps and one of my combination tie and spreader in position. 75

Figure 2 shows the operation of a fastening device for my tie and spreader.

Figure 3 is a horizontal section through form work at a corner thereof. 80

Figure 4 is a broken perspective of the form work of Figure 3.

Figure 5 is a section through one form of my spreader and tie.

Figure 6 shows the spreader and tie itself in perspective. 85

Figure 7 is a section through an alternative and preferred form thereof.

Figure 8 is an end view of my clamp.

Figures 9 and 10 are broken elevations of my clamp in its preferred form showing the operation thereof. 90

Figure 11 is a perspective view of the fastening device for my tie and spreader shown in use in Figure 2. 95

I will describe my invention in connection with form sections for concrete work, it being understood that it is applicable as well to built up forms and to other types of sectional forms. The sectional form which I have chosen as illustrative is one shown in Figure 4 and the other figures, and comprises standard sections having end struts 1 which in this instance are 2x4's, and a central strut 2, also a 2x4, the molding surface of the section being formed by ordinary sheathing 3 nailed or screwed on the struts. Top and bottom rails 4 and 5 are usually provided. For special purposes such as for use at corners, form sections of different dimensions or shapes may be provided. The standard form section is, say, 100 105 110

3 feet in width by 8 feet or so in height depending upon the type of work being done. A smaller section may be used on the outer form at the corners. Such a section is shown at 6 in Figure 5. Outer corner members 7 in Figure 3 and inner corner members 8 may be employed. These do not need special description; they will be clear from the drawings. It will be noted however that in my preferred construction, adjacent sections, 10 whether of standard form or of some special form, are so made and so arranged in constructing the form work that corresponding side struts 1, 1', etc. come together. In ordinary construction, as hereinabove indicated, it has been the 15 practice to fasten these together with nails, which is injurious. I provide clamps for the purpose which do not injure the forms and which enable them to be used over and over again a large number of times. These clamps in Figures 1 and 20 3, I have shown in use and have indicated broadly by the numeral 9. Clamps of this character have been covered by claims in my copending application hereinabove referred to. They have opposed jaws adapted to grip juxtaposed 2x4's and 25 hold them together. In Figures 9 and 10, the lower jaw is 10, and is attached to a sheet metal body 11 of generally U-shaped cross section. The upper jaw 12 has a preferably integral extension 13 attached thereto at right angles. The 30 upper part of the body of the clamp is cut away as at 14 to permit the extension 13 to slide therein and in order to define a space for this sliding movement, a member 15 is fastened within the casing or body. For convenience in operation, 35 a thumb rest 16 may be attached thereto. An operating handle 17 is provided, connected by links 18 to the upper jaw. It would be sufficient to pivot the clamp end of this operating lever in the body of the clamp but I prefer to provide an adjustable pivot mechanism to allow 40 for differences in the widths of members to be clamped, and to this end I pivot a pawl member 19 to my operating lever. This pawl has a series of teeth 20 at intervals, any of which may be 45 brought into engagement with a post 21 extending across the body of the clamp as will be understood. The pawl has an operating portion 22 to be engaged by the thumb or fingers of a person operating the clamp. The operating handle 17 is of general U-shape and is hollow within 50 so that the pawl may be pivoted between two extensions 17a formed by cutting the top of the operating handle away as at 23, and it is convenient to permit the post 24 upon which the 55 pawl is pivoted to extend beyond the portion 17a of the operating handle and ride in slots 25 in the body of the clamp. The post 26 by which the links 18 are pivoted to the operating lever extends also between the portion 17a and 60 serves as an abutment to prevent the pawl 19 from falling down out of an easily accessible position. This is clearly shown in Figure 9. The operation of my clamp will be clear from the several views.

65 My combined spreader and tie has preferably such a construction that that portion of it which extends between opposed form sections has sufficient stiffness to serve as a satisfactory spreader. This implies the provision of positive spacing means thereon. In order that the device may also serve as a tie, extensions are provided which may be passed through holes in the form work or between adjacent form sections, there to be caught and held in some manner, a preferable manner being hereinafter described. My pre-

ferred form of tie is illustrated in Figures 6 and 7 with a modification in Figure 5. The simplest form comprises a piece of sheet metal wider in the center than at the ends and bent up into substantially a channel form in the body portion 80 27. A sectional view through the body is shown in Figure 7. The exact configuration is not important. The bent up side members 28 forming the channel give the requisite stiffness and at the ends of these members I bend over ears 29 which serve as positive stops to permit my device to serve its spacing function. The metal of the spacer and tie is prolonged at the ends of the body portion into tongues 30 for the purpose described. In an alternative form a second section (Figure 5) of generally channel shape and indicated broadly by the numeral 31, is attached to the first section by means of rivets 32, spot welding or the like. Tongues 33 may also be bent up at the ends of section 31. Ordinarily the 85 more complex structure of Figure 5 is not necessary and represents a more expensive type. It will be understood that my combined spreaders and ties will be manufactured in a series of standard sizes for standard form work. Where 90 they extend diagonally across the forms as at 34 in Figure 3, they will be of somewhat greater length than extend directly across the forms as at 35 in Figure 1. For different thicknesses of walls, different size spreaders and ties will be 95 used. It will be seen in Figures 1, 3 and 4 how the tongues 30 of the spreaders extend through the form work between adjacent struts 1 and 1' of abutting form sections. If the forms be nailed together, it is possible also to bend over the 100 tongues 30 and to nail them; but inasmuch as my preferred form work is intended for use without nails, consequent expense and consequent damage to the forms, I make provision in my clamps for means not only to catch and hold 105 but also to tension the spreaders and ties. It will be seen in Figures 9 and 10 that the body portion 11 of the clamps is slotted as at 36. Where the tongues 30 extend between adjacent 110 struts to be held together by my clamps, the 115 tongues are inserted into the clamps through the slots 36 as the clamps are placed in position. Bringing down the operating lever 17 pulls with it the jaw 12 and its extension 13. This extension is notched out as at 37, and in its descent 120 it strikes and then bends over the tongues 30 of my spreader and ties. This is shown in dotted lines at 38 in Figure 1 and it will be clear that the function of my clamps is not only to hold 125 together adjacent form sections but also to hold 130 and to tension the tongues of my spreaders and ties. It will also be understood how the body portion 27 of my spreader holds the forms apart a desired and predetermined distance while the 135 tensioning of the tongues holds the forms in opposed relationship against the pressure of the wet concrete poured between them. I have found that the strength and tensioning factor of my spreaders and ties is far greater than the pressure 140 of concrete in the forms.

Since it is the usual practice to place spreaders not only at the sides of form sections between the struts, but also at intervals in the centers thereof adjacent the struts 2, I provide an additional fastening device for tensioning the spreaders 145 along these struts, where as will be obvious my clamps 9 are not used. It would be possible to use such clamps by placing a section of 2x4 along the side of strut 2 but this is uneconomical where a simpler fastening device may be used. Such 150

a device is indicated in Figure 11 and comprises a substantially U-shaped body of heavy sheet metal 39 slotted as at 40 for the passage of the tongue 30. An operating lever 41 is pivoted as 5 at 42 to one corner of one of the legs of the body 39. One edge of the lever is rounded off as at 43 for a purpose hereinafter to be described. At the other corner of the leg 39', a portion of the metal is bent over to form a holding strap 44 as 10 will be clearly understood from Figure 11 and the portion 45 of the metal lying between this strap and the pivot 42 is bent outwardly a little and may be provided with serrations or teeth the better to hold the tongue 30. As is shown in 15 Figure 2, adjacent the strut 2, the form work is perforated as at 46 for the passage of the tongue 30 which is carried through a slot 40 and then is bent over on the outside thereof. It will be understood from this figure also how the body portion 39 engages the strut 2. After the tongue 30 is bent over (while the lever 41 is in the position shown in Figure 11) this lever is then swung around to the position shown in that figure in dotted lines. The rounded portion 43 assists the 20 lever to ride over the bent portion of the tongue 30, and in closed position, the lever is held tightly against the leg 39' by the strap 44, while the bent over portion of the tongue 30 is tightly gripped between the lever itself and the toothed portion 25 45 of the clamp. The holding device of Figure 11 is less expensive to construct and use than my clamps 9 and I prefer to use it in form work not built up of standard sections or in connection with standard sections, where two struts do not 30 come together.

Various modifications may be made in my invention without departing from the spirit thereof.

Having thus described my invention, what I claim as new and desire to secure by Letters Patent is:—

1. A clamp for concrete forms comprising in combination a body, a pair of jaws and an operating handle having a pivot, one of said jaws fixed to said body, the other of said jaws having means 45 whereby it is slidable in said body so as to be moved toward or away from the other jaw, a link operatively connecting said slidable jaw with said operating handle, and adjustable means for mounting the pivot of said operating handle on said body at different effective points.

2. A clamp for concrete forms comprising in combination a body, a pair of jaws and an operating handle, one of said jaws fixed to said body, the other of said jaws having means whereby it is slidable in said body so as to be moved toward or away from the other jaw, a link operatively connecting said slidable jaw with said operating handle, and adjustable means for pivoting said operating handle on said body at different effective points, said body having an aperture to admit the end of a tie, said sliding jaw having means to contact and bend said tie end as it is moved whereby said clamp may be caused to fasten said tie.

3. In a clamp for concrete forms, a hollow body member, a pair of jaws and an operating handle, one of said jaws fixed to said body, the other of said jaws having an extension slidable in said body whereby said jaw may be moved, an abutment within said hollow body portion, a movable trigger member pivoted to said operating handle and having a plurality of engagement surfaces for said abutment and a link connecting said movable jaw with said operating handle.

4. In a clamp for concrete forms, a hollow body member, a pair of jaws and an operating handle, one of said jaws fixed to said body, the other of said jaws having an extension slidable in said body whereby said jaw may be moved, 80

an abutment within said hollow body portion, a movable trigger member pivoted to said operating handle and having a plurality of engagement surfaces for said abutment and a link connecting said movable jaw with said operating handle, said body member having a perforation to admit the end of a tie, the extension of said movable jaw being arranged when said jaw is moved to contact and bend said tie end thereby and fastening it. 90

5. In a clamp, a body portion of sheet metal comprising a back and opposed interspaced sides, a pair of jaws and an operating handle, one of said jaws fixed in said body portion so as to extend beyond the back thereof, the other of said jaws having an extension slidable between said opposed side members of said body, said operating handle having a pivot member extending through a slot in said opposed sides, a movable trigger mounted on said pivot member, 100 an abutment member extending between said sides and a plurality of engagement surfaces on said trigger whereby the effective position of said pivot member with respect to said body may be varied, and a link connecting said operating handle at a point interspaced from said pivot member with said movable jaw. 105

6. In a clamp, a body portion of sheet metal comprising a back and opposed interspaced sides, a pair of jaws and an operating handle, 110

one of said jaws fixed in said body portion so as to extend beyond the back thereof, the other of said jaws having an extension slidable between said opposed side members of said body, said operating handle having a pivot member 115 extending through a slot in said opposed sides, a movable trigger mounted on said pivot member, an abutment member extending between said sides and a plurality of engagement surfaces on said trigger whereby the effective position 120 of said pivot member with respect to said body may be varied, and a link connecting said operating handle at a point interspaced from said pivot member with said movable jaw, said body member having a perforation to admit the end 125 of a tie, the extension of said movable jaw being arranged when said jaw is moved to contact and bend said tie end thereby fastening it.

7. A fastening device for concrete form work comprising a substantially U-shaped member 130 adapted to embrace a structural element and a tie member extending there-across, the said U-shaped member perforated adjacent the base thereof for the passage of said tie member, and means to fasten said tie member on said U-shaped member.

8. A fastening device for concrete form work comprising a substantially U-shaped member adapted to embrace a structural element and a tie member extending there-across, the said U-shaped member perforated adjacent the base thereof for the passage of said tie member, and means to fasten said tie member on said U-shaped member, said means comprising a lever pivoted on a leg of said U-shaped member and 140 adapted to contact said tie member when bent over thereagainst, and an extension on said leg adapted to engage and hold said lever when in closed position. 145

9. A concrete form construction clamp com- 150

prising a frame, jaws on said frame, one movable and the other adjustable to different fixed positions on said frame, a lever to move the jaws, and a fulcrum for said lever, adjustable on said frame, and means moved by the lever to clamp a tie.

10. A concrete form construction clamp comprising a frame, jaws on said frame, one movable whereby the jaws may clamp an abutment, 10 a toggle to move said movable jaw and hold it in clamping position, and means moved by said toggle and held thereby, to clamp a tie.

11. A concrete form construction clamp comprising a frame, jaws on said frame, one movable whereby the jaws may clamp an abutment, 15 a lever fulcrumed on said frame and having a handle, a link connecting said movable jaw to said lever between the fulcrum and the handle,

and means moved in unison with said movable jaw to clamp a tie.

12. A U-shaped frame to straddle an abutment, having a slot in one side to receive a tie from alongside the abutment outwardly therethrough, and a lever fulcrumed on said side to swing past said slot and bend the tie reversely around an edge of the slot.

13. A clamp comprising a frame with a fixed jaw and a movable jaw thereon and having a slot between the jaws to receive a tie therethrough when the jaws straddle and clamp an abutment, the movable jaw having a part to slide past said slot and bend the tie over an edge of the slot when the jaws clamp the abutment, and means for moving said movable jaw.
